US0D1055919S

(12) **United States Design Patent** (10) Patent No.: **US D1,055,919 S**
(45) Date of Patent: ** Dec. 31, 2024

(54) **SMARTWATCH**

(71) Applicant: **Creek Wearable Technology Co., Ltd.**,
Shenzhen (CN)

(72) Inventors: **An He**, Shenzhen (CN); **Kexin Tong**,
Shenzhen (CN); **Yichen Tan**, Shenzhen (CN)

(73) Assignee: **Creek Wearable Technology Co., Ltd.**,
Shenzhen (CN)

(**) Term: **15 Years**

(21) Appl. No.: **35/519,494**

(22) Filed: **Nov. 20, 2023**

(80) **Hague Agreement Data**

Int. Filing Date: **Nov. 20, 2023**

Int. Reg. No.: **DM/233883**

Int. Reg. Date: **Nov. 20, 2023**

Int. Reg. Pub. Date: **Dec. 22, 2023**

(30) **Foreign Application Priority Data**

Oct. 13, 2023 (CN) 202330663576.6

(51) LOC (14) Cl. **14-02**

(52) U.S. Cl.
